(57) **CLAIM**

The ornamental design for a solar panel, as shown and described.

DESCRIPTION

FIG. 1 is a first perspective view of a solar panel showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a folded state of the solar panel thereof;

FIG. 10 is an unfolded state of the solar panel thereof;

FIG. 11 is another unfolded state of the solar panel thereof;

FIG. 12 is the using state of the solar panel thereof;

FIG. 13 is the using state of the solar panel thereof; and,

FIG. 14 is an enlarged view of the selected portion 14 in FIG. 1.

The broken lines shown in the drawings depict portions of the solar panel that form no part of the claimed design.
